UNITED STATES PATENT OFFICE.

NELS JACOBSON, OF RIBLAKE, WISCONSIN.

DESIGN FOR A PENHOLDER.

SPECIFICATION forming part of Design No. 35,577, dated January 14, 1902.

Application filed November 16, 1901. Serial No. 82,602. Term of patent 7 years.

To all whom it may concern:

Be it known that I, NELS JACOBSON, a citizen of the United States, and a resident of Riblake, in the county of Taylor and State of Wisconsin, have invented and produced a new and original Design for a Penholder, of which the following is a full, clear, and exact description.

Reference is to be had to the accompanying drawings, forming part of this specification, in which similar characters of reference indicate corresponding parts in both figures.

Figure 1 is a side view of a penholder embodying my new design, and Fig. 2 is a view of the opposite side thereof.

The essential features of the design consist in the penholder formed with an indentation *a* in its top, an indentation *b* in its

side adjacent to, yet rearward of, the indentation *a*, and an indentation *c* at the side opposite the side having the indentation *b*, the indentation *c* lying slightly forward of the indentation *a*. 20

Having thus described my invention, I claim as new and desire to secure by Letters 25 Patent—

The design for a penholder, as herein shown and described.

In testimony whereof I have signed my name to this specification in the presence of 30 two subscribing witnesses.

NELS JACOBSON.

Witnesses:

JNO. J. VOEMASTEK,
D. MCLENNAN.
